UNITED STATES PATENT OFFICE

HUBERT K. KRANTZ, OF LONG ISLAND, NEW YORK

FUSE-SWITCH PANEL

Application filed August 19, 1926. Serial No. 130,202.

This invention relates to a fuse switch panel and particularly to means by which great compactness and consequent efficiency may be attained in the provision of current controlling devices the present invention being in some respects an improvement over what is shown and described in my co-pending application Serial No. 130,201.

A more specific object is to provide means whereby the total space required to accommodate a given number of switch elements and their fuse elements within or upon a panel is reduced without detrimental sacrifice of insulating qualities.

15 A further specific object is to provide a fuse switch panel made up of units of novel construction each for controlling one or more circuits and designed so that a greater number of units may be assembled within a given 20 space than in the structure disclosed in said co-pending application.

A still further specific object is to provide an improved fuse switch block or unit in which the fuses and switches are so arranged 25 that, without sacrifice of safety with regard to the insulation of its component current carrying elements, the block or unit may be made of less width than the blocks or units disclosed in said co-pending application.

30 Other objects and aims of the invention, more or less specific than those referred to above, will be in part obvious and in part pointed out in the course of the following description of the elements, combinations, arrangements of parts and applications of 35 principles constituting the invention; and the scope of protection contemplated will be indicated in the appended claims.

In the accompanying drawings which are 40 to be taken as a part of this specification, and in which I have shown merely a preferred form of embodiment of the invention:—

Fig. 1 is a front elevational view of a fuse 45 switch panel constructed in accordance with this invention, the protecting cover door being shown partly broken away to disclose the fuse switch blocks or units arranged therebeneath, and the circuits through the fuses being illustrated diagrammatically.

Fig. 2 is a transverse sectional view taken upon the plane of line II—II of Fig. 1.

Fig. 3 is a plan view illustrating a modification in which the fuse switch blocks or units are of what may be referred to as a "double" 55 type, and

Fig. 4 is a view similar to that seen in Fig. 3 but illustrating a different arrangement of the switch receiving recesses.

Referring to the drawings for describing 60 in detail the invention as illustrated therein, the reference character I indicates a protecting casing such as commonly comprises a part of switch panel construction, said casing including a bottom wall 1, confining side 65 walls 2—2 and a top or front wall 3. The wall 3 has a central opening 4 through which the fuse blocks or units as 5—5 are readily accessible, and this opening is covered by a door G customarily supported by a hinge 70 as 6 so that it may be swung to and from closed position protecting the fuses and switches at will.

The fuse switch blocks or units 5—5 are substantially identical with each other and 75 only one need therefore be described in detail. They are made of insulating material, such as porcelain, Bakelite, or other suitable material.

An appropriate cavity or recess as 7 is provided opening outwardly through the front face of the block or unit adjacent one end of the unit. Within this cavity is carried the switch mechanism H. The switch mechanism may be of any desired type or construction 80 and a part thereof, as the operating handle 8, 85 projects outwardly through a suitable slot as 9 for the convenient manual operation of the switch mechanism. A cover plate as 10 may be provided over the recess to protect the 90 switch mechanism in the recess 7, the slot 9 being formed through said cover plate in such manner as to properly accommodate movement of the handle 8 to and from "on" position, as will be readily understood.

Other appropriate cavities at 11 and 12 are provided opening outwardly through the front face of the unit adapted to receive the usual fuse plugs as 13 and 14 respectively, and it is a particular feature of this invention 100

to arrange these cavities, and consequently the fuse plugs 13 and 14, in substantial alignment with each other longitudinally of the unit in a direction away from the switch H , as by this means the width of the unit, that is the distance between its opposite side walls as 15 and 16, need not be greater than is required to efficiently accommodate the width of a single fuse plug.

10 By so constructing the unit as to accommodate the fuses side by side lengthwise of the unit the length of the unit is not objectionably increased, but rather to the contrary since an increase in length is desirable in order to 15 maintain an attractive symmetric appearance for the panel board especially where a large number of units are arranged side by side in the panel. The reduction in width however, made possible by the longitudinal alignment 20 of the fuses, is a matter of prime importance in that it enables a considerably greater number of units, and consequently a corresponding increase in circuit number capacity, for any given size of panel, all as set forth in said 25 co-pending application.

The units are formed with a suitable recess as 17 on their under sides designed to accommodate the usual bus bars 18, 19 and 20, and each is provided with a shoulder or like part 30 as 21 for engagement by the marginal edge portions surrounding the opening 4 of the top wall 3 for retaining the units collectively in their appointed position within the opening 4.

35 The manner in which the bus bars are electrically connected with the switch mechanism is illustrated diagrammatically by wires 22 and 23 in Fig. 2, and the manner in which the fuses are connected between the switch mechanism and the line is diagrammatically shown in Fig. 1 indicated by wires 24 and 25 for fuse 13 and wires 26 and 27 for fuse 14, it being understood that the mechanical embodiment of means providing electrical connections between the bus bars and the switch 45 and between the switch and the fuses is not specifically pertinent to the present invention.

The structure as thus far described is substantially the same as is disclosed in the co-pending application referred to, wherein the 50 cavities or recesses for receiving the switch mechanisms H are bounded by walls of insulating material on all four sides, the recesses being open only at the top. The nature of the improvement thereon as suggested by the 55 present invention consists in forming the units so that the switch receiving recesses thereof have opposite side walls in the direction of length of the unit only, the side walls in the direction of the width of the unit, as 60 illustrated in the co-pending application, being omitted and the transverse width of the unit being thereby diminished by the thickness of said walls. To this end the recess as illustrated in Figs. 1 and 2 herein open 65 through the opposite sides of the unit.

Also the present improvement consists in so forming the units that by arranging them in panel form, that is in a row side by side, with each succeeding unit longitudinally reversed with respect to its neighbor, the units at opposite sides of any given unit will provide ample walls as 28 and 29 of insulating material to properly define, close and insulate the switch recess of the given unit. This is accomplished by simply arranging the recess at 70 one side of the middle of the length of the unit.

By this simple expedient the width of the unit is reduced to the bare requirements for 75 accommodating the width of the switch mechanism, no allowance for thickness of insulating walls being required. In practice it is found that one-half to three-quarters of an 80 inch may thus readily be saved in the width of the unit.

Blank units or plain slabs as 30 of insulating material may be employed to close the outer side of the switch recess of the last unit in any panel or row.

In the modification Fig. 3 the structure 90 there illustrated is identical in all respects to the structure already described except that it suggests a "double" form for the units 5, that is a form in which the length of the unit is substantially doubled so as to carry 95 two sets of switches and fuses, one-half of the length of the unit being made to accommodate one switch device and its two fuses as above set forth with respect to the units of Fig. 1, and the other half being made 100 to accommodate a duplicate switch and two fuses, the two switches of this double unit are arranged adjacent the centre of the unit and the two sets of fuses are substantially aligned with each other longitudinally of 105 the unit and beyond the switches in opposite directions so that all of the fuses and switches of the unit are substantially in alignment longitudinally of the unit thereby providing double circuit number capacity for the unit. 110

In order that units of this double capacity may partake of the advantages of the present invention the switch receiving cavities, here designated by the reference characters 31 and 32, are closed by transverse side walls 115 33 and 34 at one side of the unit only, the opposite side of the cavity being left open and adapted to be closed by the walls 33 and 34 of the next succeeding unit. By this arrangement the width of the unit is reduced 120 to an extent corresponding to the thickness of one of the side walls 33 and 34 instead of by twice this thickness as is the case with the structure Fig. 1.

In the modification Fig. 4 the structure 125 is substantially the same as in Fig. 3 except that the switch recess 32 has its transverse side wall, here designated by the reference character 35, on the opposite side of the recess as compared with the structure Fig. 3, the 130

transverse side wall 33 of recess 31 being unchanged. By this arrangement the open side of the recess 31 of a given unit is adapted to be closed by the side wall as 33 of one unit and the open side of the second recess, as 32, of the given unit is adapted to be closed by the next adjacent unit on the opposite side of the given units.

Such units as those which are illustrated in Figs. 3 and 4 are adapted for use in the building of panel structures where a larger number of branch circuits are to be provided for than would be desirable for the structure Fig. 1, but it is pointed out that either of these panel structures may be built up of an indefinite number of units according to requirements and according to the shape of the space available to accommodate them, the use of "single" units as in Figs. 1 and 2 requiring a relatively longer and narrower space for a given number of circuits than the use of "double" units as per Figs. 3 and 4.

In order that the cover plates 10 in all of the structure described may properly cover the switch recesses said plates may if desired be made of sufficient width so as to provide portions as 36—36 arranged to lap over the next adjacent unit and thereby efficiently close the joint between the two units in the region of the switch recesses.

While the invention is hereinabove particularly set forth in its relation to the building up of panels and the like from individual units it is not intended to be limited in this regard since obviously its advantages are attained not only through the use of units in which the switch recesses are open at one or more sides and intended to be closed by abutting parts of adjacent units, but also by the novel relative arrangement of the switch and fuse elements in the completed panel, namely with the switch recesses flanked on two or more sides by fuse elements so that the insulating material surrounding the fuse sockets is available also to provide a wall or walls for the switch recess.

It is further to be noted that although this invention is particularly concerned with the arrangement of fuse and switch elements in units or panel structures, nevertheless it is not necessarily restricted in this regard as obviously other elements or devices requiring insulated positions with respect to each other may be arranged as herein suggested with equally advantageous results.

As many changes could be made in this construction without departing from the scope of the invention as defined in the following claims, it is intended that all matter contained in the above description or shown in the accompanying drawings, shall be interpreted as illustrative only and not in a limiting sense.

Having thus described my invention, what

I claim as new and desire to secure by Letters Patent is:—

1. A unit adapted to be used as one of a series of similar units arranged side by side in panel-like formation, said unit being formed of insulating material and having a recess therein adapted to contain an electrical device, and said unit being formed with said recess opening through the sides of the unit arranged to be closed by abutting parts of adjacent units. 70

2. A unit adapted to be used as one of a series of similar units arranged side by side in panel-like formation, said unit being formed of insulating material and having a recess therein adapted to contain an electrical device, and said recess opening through at least one side of the unit arranged to be closed by an abutting part of an adjacent unit. 80

3. A switch unit adapted to be used as one of a series of similar units arranged side by side, said unit including a switch mechanism and having a recess therein containing at said switch mechanism, and said recess opening through at least one side of said unit and being arranged to be closed by an abutting part of an adjacent unit. 85

4. An elongated fuse switch unit adapted to be used as one of a series of similar units arranged in a row side by side with their longer dimensions transverse to the length of the row, said unit including a switch mechanism and a plurality of fuses all arranged so as to stand substantially in alignment longitudinally of the unit, the unit having a recess therein at one side of the middle of its length adapted to contain the switch mechanism, and said recess opening through the opposite side walls of the unit adapted to be closed by wall parts of adjacent units. 100

5. A fuse switch panel made up of a plurality of independently formed fuse switch units arranged side by side in a row, said units each having a recess therein to receive its respective switch mechanism, said recesses opening through the opposite sides of the unit and being at one side of the middle of the length of the unit, and the successive units in the panel being longitudinally reversed with respect to each other so that the recess of each unit is sandwiched between a relatively non-recessed portion of two adjacent other units. 110

6. A unit adapted to be used as one of a series of similar units arranged side by side in panel-like formation, said unit being formed of insulating material and having a recess therein adapted to contain an electrical device, said recess opening through a plurality of lateral sides of the unit and being disposed for being closed by wall parts of the other units. 120

7. A fuse switch panel comprising a base of insulating material made up of a plurality of independently formed sections arranged side by side, each section having a switch re- 130

cess therein and a fuse recess therein, and said sections being disposed with respect to each other so that the walls of the fuse recesses respectively constitute angularly related walls for the switch recesses.

8. A fuse switch panel made up of a plurality of independently formed fuse switch units arranged side by side in a row, said units each having a recess therein to receive an electrical device, said recesses opening through at least one side of the respective units and being closed by a wall part of the next adjacent unit.

9. A unit adapted to be used as one of a series of similar units arranged side by side in panel-like formation, said unit being formed of insulating material and having a recess therein adapted to contain an electrical device, said recess opening through at least one side of the unit arranged to be closed by an abutting part of an adjacent unit, and a cover for said recess having a portion extending to overlap a portion of the adjacent unit.

10. A unit adapted to be used as one of a series of similar units arranged side by side in panel-like formation, said unit including a switch mechanism and having a recess therein containing said switch mechanism, said unit including also a cover for said recess having an opening therethrough, and a handle for the switch mechanism operable through said opening, said recess opening through at least one side of said units adapted to be closed by an abutting part of an adjacent unit, and said cover having an extending portion adapted to overlie the abutting part of said adjacent unit.

In testimony whereof I affix my signature.
HUBERT K. KRANTZ.
